UNITED STATES PATENT OFFICE

JOHN F. FARMER, OF INDIANAPOLIS, INDIANA

ADJUSTABLE GUARD FOR OPENINGS

Application filed July 24, 1929. Serial No. 380,731.

This invention relates to an adjustable guard that is designed to be used as a measure of protection at an opening in a building or elsewhere, as at a doorway, or a window, or on a screen door, the invention having reference more particularly to a guard that may readily be adjusted as to dimensions of openings or a door before fastening it in place, without detaching parts thereof in making adjustments.

An object of the invention is to provide an improved adjustable guard for openings which shall be of such construction as to be adapted to prevent entrance into a window opening or to prevent damage to the frail wire screen commonly used on screen doors.

Another object is to provide a metallic guard which shall be so constructed as to be adapted to be readily adjusted without necessitating the use of a tool or tools, and which shall permit the passage of light and atmospheric air with no serious obstruction through it when in place.

A further object is to provide an adjustable metallic guard for openings which shall be of such construction as to be adapted for inexpensive manufacture and yet be strong, durable and economical in use.

With the above-mentioned and other objects in view, the invention consists in a novel extensible or contractible frame and novel wire lattice-work connected thereto in a novel manner to permit rapid adjustment of the frame to effect variation thereof dimensionally, the invention consisting also further in the parts and combinations and arrangements of parts as hereinafter particularly described and further more definitely claimed.

Referring to the accompanying drawings,—Figure 1 is a front plan view of the improved guard in which one portion is shown as when contracted in one direction and expanded in another direction, the remaining portion being shown as when elongated in one direction and contracted in an-

other direction; Fig. 2 is a reproduction on an enlarged scale of a portion of Fig. 1 and having portions cut away to disclose working parts; Fig. 3 is an enlarged fragmentary section, as on the line X—X on Fig. 1 which indicates a division of two portions of the guard that are differently adjusted; Fig. 4 is a fragmentary section on an enlarged scale showing lower portions of Fig. 1; and Fig. 5 is a perspective view of a section of each one of a plurality of extensible or contractible frame rails embraced in the invention.

Similar reference characters in the different figures of the drawings indicate corresponding elements or features of construction herein referred to in detail.

A practical embodiment of the invention comprises two sectional frame side rails A and B which in practice are usually arranged horizontally and has upper and lower rails respectively; and two sectional end rails C and D which in practice are usually vertical. The rails are composed of suitable sheet metal, and all the rail sections are substantially alike except as to dimensions. The rail sections may be variously constructed as to details conforming to the conception of invention that each rail shall be longitudinally adjustable and adjustably hold parts of adjustable lattice-work.

As preferably constructed each rail has an outer section comprising a base or back plate 1, a curved face portion 2 continuing from the base plate, a guide bar portion 3 extending inwardly or backwardly under the curved portion intermediately between it and the base plate. Each rail has also a similar inner section comprising a base plate 1', curved face portion 2' and a guide bar portion 3'. The inner section is longitudinally shiftable within the outer section and the sections are frictionally held together.

One end portion of each outer rail section preferably has an ear 4 thereon, each inner rail section having an ear 4' on one end there-

of, and each ear has a pivot hole 5 therein receiving a hollow pivot 6 whereby two ears are pivotally connected together, the ear of an outer section being connected to the ear of an inner section, as preferably arranged. 5 Preferably also each ear has a perforation 5' to receive a securing screw or nail whereby to secure a guard to a structure.

A suitable lattice is provided which comprises cylindrical cross bars 7 and 7' which preferably are composed of drawn steel wire and woven together as in making a screen, each bar having an end portion loosely arranged between a guide plate 1' and an opposite guide portion 3 and having also a crook 8 that extends about the edges of the guide bar portion and into the space between said portions and the face portion of the rail sections, most of the lattice bars being so connected with the side rails and a number of them with the end rails as to be shiftable therein. The lattice bars are oppositely offset at their crossing points 9, so that during adjustments slight pivotal movements occur 25 at the crossing of the bars while the crooks are shifted in the rails.

In practical use, the dimensions of an opening, or of a screen door frame being given, the guard frame is adjusted thereto by applying slight force or jarring longitudinally to the side frame rails until the end rails are spaced apart as may be required, after which the frame is secured in place by means of fasteners inserted in the hollow pivot 6, or 30 in the perforations in the ears. When fastened in place the guard protects the opening where applied against passage of animals and other depradators through the opening, and effectually protects screening of ventilating doors against rough or careless treatment or abuse of those using the screen doors.

What is claimed is:

1. An adjustable guard including a frame comprising two side rails and two end rails 45 having each an outer hollow section and an inner hollow section shiftable therein, each section being open at one side thereof and having an inwardly extending guide bar on one side of the opening, one end of each 50 outer section being connected to one end of an inner section, and offset interwoven wire lattice bars extending loosely into said openings and having each a crook shiftably guided on one of said guide bars.

2. In an adjustable guard, the combination of a frame rail comprising a section having a flat base plate and a continuing face portion provided on its terminal edge 60 with an inward-extending guide bar portion arranged opposite to said base plate, the bar portion being narrower than the plate; and a wire lattice comprising interwoven bars having ends guided on said base plate 65 and provided with crooks extending loosely

over the edge of said guide bar portion adjacent to said face portion.

3. In an adjustable guard, the combination of a plurality of frame rails comprising each an outer section and an inner section therein, one end portion of each section having an ear thereon, and the ears of the outer sections being pivotal to the ears of the inner sections of adjacent rails; and a plurality of interwoven cylindrical wires adjustably connected 75 with said rails.

In testimony whereof, I affix my signature on the 19th day of July, 1929.

JOHN F. FARMER.
